HARRY E. ASHWORTH AND BRANKO LAZICH, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA

ELECTRICAL RELAY

Application filed September 30, 1929. Serial No. 396,225.

Our invention relates to electrical relays. One object of our invention is the provision of means for automatically compensating for the effects of changes in the ambient temperature upon the time constants of a relay.

We will describe one form of relay embodying our invention, and will then point out the novel features thereof in claims.

The accompanying drawing is a view, partly diagrammatic, illustrating in isometric projection one form of an electrical relay embodying our invention.

Referring to the drawing, the reference character A designates an electromagnet which, in the form here shown, comprises three magnetizable cores 1, 2 and 3, connected together at their upper ends by a back strap 4, and provided at their lower ends with enlarged pole pieces 1^a, 2^a and 3^a, respectively. The core 1 carries an energizing winding 5, and the core 3 carries a similar energizing winding 6. The pole piece 2^a is bifurcated, and a magnetizable armature 7 is pivotally supported between the bifurcations of the pole piece 2^a, for swinging motion toward one or the other of the pole pieces 1^a or 3^a. Attached to the underside of the armature 7 by means of suitable insulating supports 8, only one of which is shown in the drawing, are two contact fingers 9 and 10. When armature 7 is swung toward pole piece 3^a, as shown in the drawing, contact finger 9 engages a fixed contact member 9^a to close a contact 9-9^a, and contact finger 10 then engages a fixed contact member 10^b to close a contact 10-10^b. When armature 7 is swung toward pole piece 1^a, however, contact finger 9 engages a fixed contact member 9^b to close a contact 9-9^b, while contact finger 10 engages a fixed contact member 10^a to close a contact 10-10^a.

The windings 5 and 6 of relay A are connected in series and are supplied with current from a suitable source of energy, here shown as a battery 15. It will be seen from an inspection of the drawing, however, that when contact 9-9^a is closed, winding 6 is short-circuited; and that when contact 9-9^b is closed, winding 5 is short-circuited. The supply of current to the relay may be con-

trolled in any suitable manner, such as by a manually operable switch 16.

As shown in the drawing, switch 16 is open and armature 7 is swung toward the pole piece 3^a so that contacts 9-9^a and 10-10^b are closed. If, now, switch 16 is closed, current flows through winding 5, but since contact 9-9^a is closed, winding 6 is short-circuited, and winding 6 therefore remains de-energized. The energization of winding 5 sets up a flux in core 1 which causes armature 7 to swing toward pole piece 1^a. During this motion of the armature, however, contact 9-9^a opens and contact 9-9^b closes. The closing of contact 9-9^b short-circuits winding 5, and the field set up in core 1 by this winding commences to decay. Due, however, to the short-circuited winding, this decay is comparatively slow. The opening of contact 9-9^a in the meantime has allowed winding 6 to become energized. The growth of the field set up in core 3 by current in this latter winding is comparatively rapid and, after a time, the torque exerted on armature 7 by the decreasing flux in core 1 will be overbalanced by the torque exerted on armature 7 by the flux in core 3, so that armature 7 swings toward pole piece 3^a. This motion will first open contact 9-9^b and then close contact 9-9^a. The field of winding 5 will then rapidly build up and the field of winding 6 will slowly decay, this decay being retarded by the inductance of winding 6. Eventually the torque exerted by the flux in core 3 will not be sufficient to hold the armature, and the armature will then again swing toward the pole piece 1^a. It will, therefore, be apparent that armature 7 is swung to and fro as long as switch 16 is closed, and it will also be clear that a considerable time interval elapses between armature movements.

In a relay of the type described, the time interval which elapses between successive armature movements is substantially independent of fluctuations in the electromotive force of the energy supply because the armature is acted upon by two opposing forces, both of which increase or decrease as the electromotive force of the energy supply increases or

decreases. If the ambient temperature increases, however, the impedances of the windings 5 and 6 increase, and the time interval which elapses between successive armature movements, therefore, increases. This increase is undesirable, and we have found that this increase may be prevented by connecting the pole pieces of the electromagnet by an auxiliary magnetic path, the reluctance of which is increased as the temperature increases. As here shown, this path comprises a magnetizable shunting member 11, pivotally supported on a pin 17 carried by a downwardly extending projection of one of the bifurcations of the pole piece 2^a, and arranged to swing toward or away from the pole pieces 1^a, 2^a and 3^a. Attached to the member 11 is a device which changes its shape in response to changes in its temperature. As here shown, this device is a bimetallic strip 12, attached intermediate its end to member 11, and arranged in such manner that its free ends 12^a and 12^b will deflect toward or away from the pole pieces 1^a and 3^a, respectively, according as the ambient temperature increases or decreases. A pin 13 is attached to the pole piece 1^a and extends with some clearance through a hole 11^a in the member 11, and a similar pin 14 is attached to the pole piece 3^a and extends through a hole 11^b in the member 11. When relay A is operating, the fluxes set up in the cores 1 and 3 exert a force on the member 11 which moves the member 11 to a position in which the ends 12^a and 12^b of the strip 12 engage the pins 13 and 14, respectively. The lengths of the pins 13 and 14 are such, and the strip 12 is so arranged, that at a given temperature, preferably the normal operating temperature of the relay, the member 11 is spaced from the pole pieces 1^a, 2^a and 3^a by the proper air gap to cause the relay armature to operate at the desired rate. It will be apparent, therefore, that if the ambient temperature increases, the resultant deflection of the bimetallic strip 12 will move the member 11 away from the pole pieces 1^a, 2^a and 3^a, thereby increasing the reluctance of the magnetic path including the member 11, and hence increasing the percentage of the total flux set up in the cores 1 and 3 which threads the armature 7, so that the armature has a tendency to operate more rapidly. If the ambient temperature decreases, however, the resultant deflection of the bimetallic strip 12 will permit the member 11 to move toward the pole pieces 1^a, 2^a, and 3^a, thereby decreasing the reluctance of the magnetic paths including the member 11, and hence shunting away from the armature 7 a greater percentage of the total flux set up in the cores 1 and 3, so that the armature 7 tends to operate more slowly. The parts are so proportioned that the variations in the reluctance of the magnetic path including the member 11 will compensate for the variations of the time inter-

val which elapses between successive armature movements as a result of temperature changes. It will be apparent, therefore, that in a relay constructed in accordance with our invention, the time interval which elapses between successive armature movements is unaffected by variations in the electromotive force of the energy supply, or by changes in ambient temperature, and the time interval between successive armature movements therefore, remains practically constant. 75

Relays embodying our invention are particularly suitable for, although in no way limited to, use for periodically interrupting an electric circuit in which a constant open 80 or closed time is desired.

Although we have herein shown and described only one form of electrical relay embodying our invention, it is understood that various changes and modifications may be made therein within the scope of the appended claims without departing from the spirit and scope of our invention. 85

Having thus described our invention, what we claim is:

1. In combination, an electromagnet, an armature controlled by said electromagnet, an auxiliary magnetic path between the pole pieces of said electromagnet for shunting a portion of the flux from said electromagnet 90 away from said armature, and means for varying the reluctance of said path in response to variations in the ambient temperature.

2. In combination, an electromagnet, an armature controlled by said electromagnet, an auxiliary magnetic path between the pole pieces of said electromagnet for shunting a portion of the flux from said electromagnet 10 away from said armature, and means for increasing the reluctance of said path in response to increases in the ambient temperature.

3. In combination, an electromagnet, an armature controlled by said electromagnet, a magnetizable shunting member spaced from each pole piece of said electromagnet by an air gap, and means for varying said air gaps in response to variations in ambient temperature. 110

4. In combination, an electromagnet, an armature controlled by said electromagnet, a magnetizable shunting member spaced from each pole piece of said electromagnet by an air gap, and means for increasing said air gaps in response to increases in the ambient temperature. 120

5. In combination, an electromagnet, an armature controlled by said electromagnet, a magnetizable shunting member spaced from each pole piece of said electromagnet by an air gap, and a device which changes its shape in response to changes in its temperature for at times varying said air gaps. 125

6. In combination, an electromagnet, an 130

armature controlled by said electromagnet, a magnetizable shunting member spaced from each pole piece of said electromagnet by an air gap, and a bimetallic strip which deflects when heated attached to said shunting member in such manner that deflection of said strip varies said air gaps.

7. In combination, an electromagnet having two pole pieces, an armature controlled by said electromagnet, a movable magnetizable shunting member spaced from each said pole piece by an air gap for shunting a portion of the flux from said electromagnet away from said armature, a bimetallic strip attached to said member and having one end free to deflect in response to variation in ambient temperature, and a pin attached to one said pole piece and arranged to engage the free end of said strip in such manner that deflection of said strip varies said air gaps.

8. In combination, an electromagnet comprising a first, a second, and a third magnetizable core connected together at their upper ends by a back strap and provided at their lower ends with a first, a second, and a third pole piece, respectively; a first winding on said first core and a second winding on said third core, a magnetizable armature pivotally attached to said second pole piece and arranged to swing toward said first or said third pole piece according as said first or said second winding is energized, a magnetizable shunting member supported for movement toward or away from all of said cores simultaneously, a bimetallic strip which deflects when heated and attached intermediate its ends to said member and arranged in such manner that its free ends will deflect toward or away from said first and third pole pieces respectively according as the ambient temperature increases or decreases, and a first and second pin attached to said first and third pole pieces respectively and arranged to engage said strip at its free ends in such manner that deflections of said strip move said member toward or away from said pole pieces according as the ambient temperature decreases or increases.

9. In combination, an electromagnet, an armature controlled by said electromagnet, an auxiliary magnetic path between the poles of said electromagnet for shunting a portion of the flux from said electromagnet away from said armature, and means for varying the reluctance of said auxiliary path with variations in ambient temperature in such manner that changes in the time constant of said relay due to changes in ambient temperature are compensated for by the variations in the reluctance of said path.

10. In combination, an electromagnet provided with a winding, an armature controlled by said electromagnet, an auxiliary magnetic path between the poles of said electromag-

net, and means for varying the reluctance of said auxiliary path with variations in temperature in such manner that changes in the time constant of said relay with changes in temperature due to changes in the impedance of said winding are compensated for by the variations in the reluctance of said auxiliary path.

In testimony whereof we affix our signatures.

HARRY E. ASHWORTH.
BRANKO LAZICH.
